UNITED STATES PATENT OFFICE.

HARVEY MILLER, OF CINCINNATI, OHIO.

HINGE-TIP.

SPECIFICATION forming part of Letters Patent No. 293,662, dated February 19, 1884.

Application filed October 20, 1883. (No model.)

To all whom it may concern:

Be it known that I, HARVEY MILLER, of Cincinnati, Hamilton county, and State of Ohio, have invented a new and useful Improvement in Hinge-Tips, of which the following is a full, clear, and exact specification, reference being had to the accompanying drawings, forming part of this statement of invention, in which—

10 Figure 1 is a perspective view of my hinge-tip. Fig. 2 is a vertical section through my hinge-tip.

Similar letters of reference in the several figures of the drawings indicate the same parts.

15 My invention relates to hinge-tips for safes, and may be used for any similar ornamental purpose.

The hinge-tips in general use are solid castings. My hinge-tip is cast about a cement or 20 other suitable substance that will withstand a crushing pressure. My hinge-tip consists of a metal casting inclosing an interior solid form. Preferably the form is made of cement. My hinge-tip is made as follows: An interior cement form is first molded, a pin is inserted into it, and it is then placed in a mold, and the metal is poured around it.

Reference being had to the drawings, C, Fig. 2, is the outer metal shell; B, the interior form, (made preferably of cement;) A, the hole in the shell C and the neck of said shell and in the form B, made by the pin inserted in the form B.

30 Among other advantages that my tip has over the ordinary solid tip are the following:

First. Lightness of weight and economy in metal.

Second. A large percentage of the solid tips

is rejected on account of blow-holes or air-holes that form in their substance in casting. 40 A hinge-tip is not salable until it is plated with nickel or some other bright metal, and if a tip having air-holes in it is plated the solution is taken up by the holes, and afterward sweats out and destroys the plating. Tips 45 made as I make them do not show these air-holes.

Third. Solid tips are wrapped in paper for shipping and then packed together, and many of them are ruined by reason of knocking together in transit. My tip is shipped without wrappers. They are held on pins inserted into the tips on racks. Every one is thus held apart from the others, and is free from danger arising from friction.

55 The advantage of my tip over a hollow tip is this: A hollow tip would be crushed by the tongs in screwing the tip into place. My tip, being filled with a non-crushable solid form, resists such pressure as would a solid 60 metal tip.

Having thus described my invention, what I claim as new, and desire to secure by Letters Patent, is as follows:

As an article of manufacture, a hinge-tip 65 consisting of an outer metal shell cast over and inclosing a pressure-resisting form, and having the screw cast hollow and integral therewith, substantially as described.

The foregoing specification of my invention 70 signed by me this 17th day of October, A. D. 1883.

HARVEY MILLER.
